UNITED STATES PATENT OFFICE

2,100,198

EXTRACTOR-CLEANER MACHINE

John E. Mitchell, Dallas, Tex.

Application January 8, 1936, Serial No. 58,079

5 Claims. (Cl. 19—37)

My invention relates to a novel extractor-cleaner machine wherein, as compared with the more generally used type of machines, a single large cleaning cylinder is employed, and the general object of the invention is to increase the efficiency of the machine by providing quickly accessible and removable working parts.

With this general object in view, my invention resides chiefly in constructing the casing of the machine in three sections, namely, a central casing section and front and rear casing sections, the latter being easily detachable at will from the central casing to permit ready access to the main working parts of the machine for repair or replacement thereof.

According to my invention the extracting and cleaning cylinders are also removably mounted in the central section to permit of quick removal of the cylinders from this section when the front and rear casing sections are detached.

It should be explained that while it is a simple matter to provide openings in the end frame portion of the casing of extractor-cleaner machines through which small rollers can be removed from the housing, this is not practicable in machines employing the larger diameter extracting and cleaning cylinders. In prior machines of this character therefore, the casing has been built around the large diameter cylinders, and to remove the cylinders for repair or replacement, it has been necessary to take apart or practically dismantle the machines, which results in very expensive delays in the operation of the gin plant equipped with such machines.

The demand in recent years for more effective cleaning and better preparation of the cotton for the extracting cylinders, has made it necessary to use a preparatory cleaning cylinder of much larger diameter than those previously employed in order to provide the screen surface needed within the space, in height, ordinarily available for the mounting of extractor-cleaner machines on the gin stands.

Attempts have been made to use a plurality of comparatively small diameter preparatory cleaning cylinders, such as disclosed in my prior Patent No. 1,906,076 of April 25, 1933; but it requires a large number of such cylinders to provide as much screen surface as can be provided within the same space, in height, by a single large diameter cylinder, and aside from the fact that the use of a large number of small cylinders is more expensive and less effective than a single large cylinder, the small cylinders have a noticeable tendency to rope, twist, and other-

wise machine the cotton as a result of its being thrown from one cylinder to another.

In actual use of extractor-cleaner machines, foreign substances, such as sacks, coats, rocks, sticks, and sometimes parts of other machinery often pass into the machines with the cotton and choke the machines down, frequently seriously damaging a cylinder; and unless the operator has quick access to the working chambers around the cylinder, or is able to quickly remove the cylinders for repair or replacement, it becomes necessary to shut the plant down long enough to practically take the machine apart and reassemble it. Such long delays are not only expensive to all concerned, but often result in loss of customers waiting to have their cotton ginned.

Aside from the expensive delays thus experienced by the users of extractor-cleaner machines of the type having the housing built around the extractor and cleaner cylinders, it is obvious that machines of such design and construction are more expensive to build or to assemble.

In machines constructed according to my invention, the middle section, which is supported on the gin stand, carries all of the cleaning and extracting cylinders, while light front and rear casing sections are made quickly detachable from the middle section, and when detached the cleaning and extracting cylinders are not only exposed for inspection but the cylinders can be quickly removed from the middle section without disturbing or removing any of the parts comprising the main housing structure.

Finally, it is to be noted that the design and construction of my improved machines makes it possible, as to the rear removable casing section, to permanently mount therein a portion, approximately one-half, of the screen partly surrounding the cleaning cylinder, which portion of the screen is of course removed with the rear casing section. In like manner, as to the front removable casing section, the doffing cylinder for the extracting cylinder is mounted in the casing section and removable with the same. Thus, when these casing sections are removed from the central section, the simultaneous removal of one-half of the screen at the rear, and of the doffing cylinder at the front, respectively, removes from the machine obstructing parts which would otherwise have to be removed from the machine in a separate operation to permit access to, or removal of, the cleaning cylinder on the one hand, or the extracting cylinder on the other.

In addition to the leading characteristics of

the invention above set forth, my invention embodies the further feature of so designing and constructing the parts with reference to the feeding rollers which supply the cotton to the machine, that such cotton is delivered to that portion of the cleaning cylinder operating within the upper portion of the middle section.

The invention is illustrated in the accompanying drawing in which Fig. 1 is a longitudinal sectional view through a machine constructed according to my invention.

Fig. 2 is a view in end elevation of the rear portion of the machine, showing the manner of detachably mounting the rear casing section on the central section, and showing also one of the side bearings for the shaft of the cleaning cylinder; and

Fig. 3 is a plan view of the end portion of the machine shown in Fig. 2, as indicated by the section line 3 and arrows in Fig. 2.

Referring now to the drawing, the numeral 4 indicates the central section of the casing, the numeral 5 the rear removable casing section and the numeral 6 the front removable casing section. Mounted in bearings 7 (Fig. 2) secured at either side of the central casing section, and near the rear edge portion thereof is the shaft 8 of the preparatory cleaning cylinder 9. This cylinder is relatively large in diameter being, in fact, two or three times as large as, and several times more effective than, the cleaning cylinder commonly used in extractor-cleaning machines. This cleaning cylinder is entirely surrounded on its lower side by a screen 10, which is made in two parts, one part, indicated by the numeral 11, constituting about one-half of the screen, being permanently mounted in the removable casing section 5 and the remaining portion being permanently mounted in the central casing 4. The main casing 4 is provided with an upward extension 12, constituting a spout for receiving the cotton to be cleaned, and in this extension are housed feed rollers 13. Below these feed rollers is mounted a directing roller 14, the arrangement and location of these members being such that the cotton forced down between the feed rollers 13 is delivered by the directing roller 14 onto that portion of the cleaning cylinder operating within the upper portion of the middle section 4 of the casing.

In Figs. 2 and 3 I have illustrated a convenient arrangement for detachably mounting the rear casing section 5 on the middle section 4. In this arrangement, I bolt to the rear edge of each side wall of the middle section 4 a bracket, 15, having an outward and upwardly curved extension, 16. Secured in the upper portion of the outer wall of the rear casing section 5 is a rod, 17, which projects beyond the sides of the casing sections and at its ends rests in the curved extensions 16. It will be understood that the rear portion of the middle section 4, covered by the casing section 5, is open, as indicated by the arrow 18, and the lower edge of this opening is provided with a short, downwardly extending flange, 19, which is adapted to receive a corresponding flange, 20, formed on the lower edge of the casing section 5. The flange 19 thus serves as a seat for the flange 20 of the casing section 5 when the latter is in the closed position shown. To permit access to the cleaning cylinder, the rear casing section 5 may be swung outward on the rod 17, which acts as a hinge or pivot for the casing section, or the latter may be entirely removed from the middle section by simply lifting it sufficiently to free the

rod 17 from engagement with the curved extension 16. With the casing section 5 lifted, or removed, the opening 18 gives ready access to the cleaning cylinder 9, as the rear portion 11 of the screen is carried by the said casing section, and consequently moved from its encircling position around the cleaning cylinder when the casing section 5 is swung outward, or removed from the middle casing 4.

As previously referred to, it is often desirable not only to inspect the cleaning cylinder, or the working space surrounding the same, to remove any obstructing material from the cleaning cylinder, but in the case of injury to said cylinder it is very important that the latter should be capable of ready removal from the machine either for repair or to permit of its replacement by another cylinder. With this object in view, the bearings 7 for the shaft 8 of the cleaning cylinder are secured by screws 19^a on the outer face of each side wall of the casing, these screws passing through apertures in a circular flange 28^a provided on each bearing and engaging in screw threaded portions of the side wall of the machine. The edge portion of each side wall of the machine is likewise provided with an open end slot 21, into which the ends of shaft 8 are inserted after which the bearings 7 are placed on the ends of the shaft and secured in position by the screws 19^a, as described.

To remove the cleaning cylinder 9 from the machine, the rear casing section 5 is first removed, the screws 19^a are unscrewed and the bearings 7 pulled off of the ends of shaft 8, when said shaft and its cylinder may be readily withdrawn by pulling the ends of the shaft out of the slots 21.

The front casing section 6 is detachably mounted on the front wall of the middle section 4 of the casing in the same manner as described with reference to the casing section 5, and it is deemed unnecessary to repeat this description. In place of the screen member mounted in casing section 5, the front casing section has mounted therein a doffing cylinder 22, the shaft 23 of which is of course, mounted in bearings (not shown) secured on the opposite side walls of the casing section. With the casing section 6 in position, as shown at the right of Figure 1, the doffing cylinder 22 is in position to doff cotton from the extracting cylinder 24, and to discharge the same through the open bottom 25 of the casing section into the gin on which the extractor-cleaner machine is adapted to be mounted.

The shaft 26 of the extracting cylinder is mounted in bearings on the side walls of the machine exactly in the same manner as described with reference to the shaft 8 of the cleaning cylinder, and may be withdrawn from the machine through slots 28^a after bearings have been removed from the shaft. The remaining parts of the machine illustrated comprising the kicker roll, 27, reclaiming cylinder, 28, cooperating with the brushes, 29, the trash roller, 30, and the conveyor, 31, for discharging trash from the machine are all features of prior art patents, mostly issued to me, and the construction and operation of which are fully understood by those skilled in the art of treating cotton.

As when the rear casing section 5 is detached from the machine the rear portion 11 of the surrounding screen is removed with the casing section to fully expose the cleaning cylinder, so when the casing section 6 is detached from the middle section the doffing cylinder 22 is re-

5 moved with it, so that free and unobstructed access is afforded to the extracting cylinder 24. And either cylinder may be readily removed without disturbing or removing any other parts of the machine.

10 The feeding rollers 13 deliver the mixed cotton and hulls to the upper portion of the preparatory cleaning cylinder 9 rotating within the central casing section 4, and after the stream is forced out and down around the screen member carried by the rear detachable casing 5, it is then forced 15 upward over that portion of the screen mounted in the middle casing 4 and delivered by the roller 14 to the extracting saw cylinder 24 which, as 20 stated, is also mounted in and partially enclosed by the central casing section 4.

25 While I have described and illustrated the use of a single extracting cylinder, I wish it understood that two or more such cylinders could be employed, which would simply necessitate a change in the design and proportions of the machine shown, without in any manner departing from the principle of the invention as herein claimed.

30 It will be seen that the chief function of the front casing section 6 is to house the doffing cylinder, to receive the cotton removed by the doffer from the extracting saw cylinder and to discharge it into the gin breast; and that the 35 chief function of the rear casing section 5 is to support the rear portion of the screen extending around the cleaning cylinder and to provide an enclosed space for receiving and collecting the trash forced through the rear portion of the screen by the cleaning cylinder. The chief purpose of the central section is to support and partially enclose the cleaning and extracting cylinders and the members cooperating therewith.

I claim:

40 1. An extractor-cleaner machine comprising a central vertical casing section having a preparatory cleaning cylinder and an extractor cylinder mounted therein at its opposite sides and projecting at one side through openings provided in the front and rear walls of said casing section, front and rear detachable casing sections 45 inclosing that portion of the cylinders projecting beyond the front and rear walls of the central casing section, a screen surrounding the lower portion of said cleaning cylinder and made in two parts, one part being mounted in the central, and the other in the rear, casing section, and a doffing cylinder for said extractor cylinder mounted in said front casing section, whereby 50 when either of said front or rear casing sections is removed, the cylinder inclosed thereby will be rendered readily accessible.

45 2. An extractor-cleaner machine comprising a central vertical casing section having a preparatory cleaning cylinder and an extractor cylinder mounted therein at its opposite sides and respectively accessible and removable through openings provided in the front and rear walls of said casing section beyond which said cylinders project, a screen partially surrounding said cleaner cylinder and made in two parts, a rear casing section detachably mounted on said central casing section and inclosing the projecting portion of said cleaning cylinder and having one part of

5 said screen mounted therein, and a front casing section detachably mounted on said central casing section and inclosing the projecting portion of said extractor cylinder and having a doffing cylinder for said extractor cylinder mounted therein, whereby when said front and rear casing sections are removed, the removal therewith of a part of said screen and of said doffing cylinder, respectively, will permit unobstructed access to, and removal of, said cylinders through their respective openings.

10 3. An extractor-cleaner machine comprising a central vertical casing section having a preparatory cleaning cylinder and an extractor cylinder mounted therein at its opposite sides and respectively accessible and removable through openings 15 in the front and rear walls of said casing section, the edge portions of said walls at either end of the machine being provided with open end slots for removably receiving the shafts of said cylinders, bearings for said shafts detachably secured to the outer sides of said walls, front and rear detachable casing sections normally closing said openings, a screen surrounding the lower portion of said cleaning cylinder and made in two parts, one part being mounted in the central, and the other in the rear, casing section, and a doffing cylinder for said extractor cylinder mounted in said front casing section, whereby 20 when either of said front or rear casing sections is removed, and the bearings detached from the shaft of the cylinder, the latter may be readily removed from the casing section through the uncovered opening by withdrawing the shaft from the slots in the central casing section.

25 4. An extractor-cleaner machine comprising a central vertical casing section having a preparatory cleaning cylinder and an extractor cylinder mounted therein at its opposite sides and projecting through openings in the front and rear walls 30 of said casing section, front and rear detachable casing sections normally closing said openings and inclosing the projecting portions of said cylinders, a doffing cylinder for said extractor cylinder mounted in and carried by the front casing section, the latter being constructed to receive the cotton removed by the doffer from the extractor cylinder and to discharge same from the machine.

35 5. An extractor-cleaner machine comprising a central, vertical casing section having a preparatory cleaning cylinder and an extractor cylinder mounted therein at its opposite sides and projecting through openings in the front and rear walls 40 of said casing section, front and rear 45 detachable casing sections normally closing said openings and inclosing the projecting portions of said cylinders, a doffing cylinder for said extractor cylinder mounted in and carried by the front casing section, the latter being constructed to receive the cotton removed by the doffer from the extractor cylinder and to discharge same from the machine, and feed rollers mounted in the central casing section and positioned to deliver cotton to that portion of the 50 cleaning cylinder operating within the central casing section.

JOHN E. MITCHELL.
